US0D1109163S

(12) United States Design Patent (10) Patent No.: US D1,109,163 S
(45) Date of Patent: * Jan. 13, 2026

(54) DISPLAY SCREEN OR PORTION THEREOF WITH GRAPHICAL USER INTERFACE

(71) Applicant: Apple Inc., Cupertino, CA (US)

(72) Inventors: Jingfang Chen, San Francisco, CA (US); Thalia Jimena Echevarria Fiol, Cupertino, CA (US); Fiona P. O'Leary, Palo Alto, CA (US); Behkish Johnnie Manzari, San Francisco, CA (US); Nicolas V. Scapell, London (GB); Raymond Sepulveda, Portland, OR (US); Chun Kin Minor Wong, San Jose, CA (US); Giancarlo Yerkes, Menlo Park, CA (US)

(73) Assignee: Apple Inc., Cupertino, CA (US)

() Term: 15 Years

(21) Appl. No.: 29/893,854

(22) Filed: Jun. 2, 2023

(51) LOC (15) Cl. 14-04

(57) CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is a front view of a display screen or portion thereof with graphical user interface showing another embodiment of the claimed design.

The peripheral dashed broken lines illustrate a display screen or portion thereof, and form no part of the claimed design.
